Primary Examiner — Jennifer L Rempfer

Assistant Examiner — Sarah A Nguyen

CLAIM

The ornamental design for a flat mop with cloth as shown and described.

DESCRIPTION

1. Flat mop with cloth
- 1.1: Perspective view 2
- 1.2: Perspective view 1
- 1.3: Front
- 1.4: Back
- 1.5: Left
- 1.6: Right
- 1.7: Top
- 1.8: Enlarged view of the top plan view
- 1.9: Bottom
- 1.10: Enlarged view of the bottom plan view

1 Claim, 10 Drawing Sheets
